UNITED STATES PATENT OFFICE

ISIDOR ROSENBLATT, OF NEW YORK, N. Y.

DESIGN FOR A LIGHTING-FIXTURE SUSPENSION LOOP OR ARTICLE OF SIMILAR NATURE

Application filed February 26, 1931. Serial No. 38,842. Term of patent 3½ years.

To all whom it may concern:

Be it known that I, ISIDOR ROSENBLATT, a citizen of the United States, residing in New York, in the county of Kings and State of New York, have invented a new, original, and ornamental Design for a Lighting-Fixture Suspension Loop or Article of Similar Nature, of which the following is a specification, reference being had to the accompanying drawing, forming a part thereof.

Figure 1 is an edge view of a lighting fixture suspension loop showing my new design.

Fig. 2 is a front elevational view thereof, in which the portions shown in broken outline involve a mere repetition of the completed portions more fully illustrated in solid lines.

I claim:

The ornamental design for a lighting fixture suspension loop or article of similar nature, as shown.

In testimony whereof I affix my signature.

ISIDOR ROSENBLATT.
